United States Patent Office

Des. 180,493

Patented June 18, 1957

180,493

MULTIPLE SPINDLE LATHE

Carroll E. Miller, Windsor, Vt., assignor to Cone Automatic Machine Company Inc., Windsor, Vt., a corporation of Vermont

Application July 25, 1956, Serial No. 42,395

Term of patent 14 years

(Cl. D54—6)

Figure 1 is a perspective view of one side and end of a multiple spindle lathe embodying my new design;

Figure 2 is a perspective view thereof illustrating the end opposite that shown in Figure 1; and

Figure 3 is a perspective view taken from the side and end opposite the side and end shown in Figure 2.

I claim:

The ornamental design for a multiple spindle lathe, as shown.
